Des. 184,089
Patented Dec. 16, 1958

184,089

EMBROIDERED NYLON FABRIC OR SIMILAR ARTICLE

Leonard Grinberg, Valley Stream, N. Y.

Application February 12, 1958, Serial No. 49,629

Term of patent 3½ years

(Cl. D92—1)

The figure is a top plan view of an embroidered nylon fabric or similar article, showing my new design.

I claim:

The ornamental design for an embroidered nylon fabric or similar article, substantially as shown.
